Lacy & Lacy, Attorneys

UNITED STATES PATENT OFFICE.

CLARENCE E. TAYLOR, OF DANVILLE, ILLINOIS.

RAILROAD TIE.

Application filed May 2, 1922. Serial No. 557,908.

To all whom it may concern:

Be it known that I, CLARENCE E. TAYLOR, a citizen of the United States, residing at Danville, in the county of Vermilion and 5 State of Illinois, have invented certain new and useful Improvements in Railroad Ties, of which the following is a specification.

My invention relates to railroad ties and has for its object the provision of a durable 10 tie which may be produced and installed at a low cost and by which the track rails will be firmly supported. The invention is illustrated in the accompanying drawings and will be hereinafter fully set forth.

15 In the drawings—

Figure 1 is a perspective view of my improved tie showing the same in operative position with track rails in transverse section;

20 Fig. 2 is a perspective view of the locking cap which is employed in connection with the tie, and

Fig. 3 is a longitudinal section through the tie showing the cap engaging a track 25 rail.

Fig. 4 is a detail section on the line 4—4 of Fig. 3.

In carrying out my invention, I employ a tie 1 which is constructed of metal, preferably with a flat top, and may be of any desired cross sectional outline, although I prefer the rectangular form illustrated in the drawings. The tie is hollow, as clearly shown, so that there is no excess weight while 30 it will possess sufficient strength to prove effectual in use. Adjacent its ends, the tie is constructed with transverse slots or openings 2 in its top and the ends of the slots are continued partly down the sides of the tie. 35

40 In the side walls of the tie and opening into the vertical sides of the slots 2 at the bases thereof are notches 3 which conform to the base flange of the track rail 4 in both form and dimension so that the said flange 45 may be snugly received in the said notches, the flange at the opposite side of the rail and the vertical web of the rail being disposed within the slots 2, as clearly shown. It will be noted that the slots 2 are constructed with

50 one vertical end wall and that the opposite wall is inclined upwardly from the base of the slot and away from the vertical end wall, and it will also be noted, particularly upon reference to Fig. 3, that the vertical 55 wall of the slot abuts the web of the rail for a considerable portion of the height of the

same. The cap also abuts the web of the rail for a considerable distance so that, when the parts are fully assembled, the track rails are very effectually braced. Notwithstanding that the track rails are thus held through contact of the tie and the cap with a considerable portion of the vertical webs of the rails, it is not necessary to slide the rails endwise into position, but the provision of the 60 inclined walls of the slots permits the rails to be brought into position over the slots and then transversely rocked so that they will pass down into the slots and slide readily into engagement with the notches in the ties. 65 When the caps are slid longitudinally of the ties, they will likewise engage the rails so that transverse movement of the rails upon the ties is effectually prevented. The described arrangement brings the vertical 70 web 5 of the track rail against the side wall of the slot into which the notches 3 open and to maintain the rail against said wall, I provide the cap 6 which is slidably mounted upon the tie and consists of a top 75 web resting upon the top web of the tie and side webs 7 bearing against the side walls of the tie, as shown and as will be readily understood. The side webs 7 are provided with openings 8 therethrough to receive bolts 9 80 whereby the cap will be firmly secured to the tie and in the edges of the side webs 7 presented to the track rail are notches 10 similar in size and shape to the notches 3 and adapted to engage the base flange of the track 85 rail, as will be readily understood. The side walls of the tie are provided with longitudinal slots 11 receiving the bolts 9 so that a sufficient longitudinal movement of the cap is 90 permitted to bring the cap into proper engagement with the rail. 95

In assembling the parts, the ties are placed in position along the roadbed and the rails are caused to engage the notches and slots in the ties. This engagement may be very 100 readily effected by a rocking movement of the rails, as hereinbefore set forth. After the rails are in position upon the ties, the caps 6 are slid along the ties to engage against the rails and force them against the abutting 105 walls of the respective slots and snugly into the several notches 3, after which the bolts 9 are inserted and secured, as will be readily understood. Upon referring particularly to Fig. 4, it will be noted that I have shown 110 the bolt constructed with a longitudinal slot to receive a tapered locking key or wedge 12.

This locking key will bind between the side of the cap and the outer end of the slot in the bolt so that the parts will be firmly secured together while threaded connections which are apt to corrode are avoided.

It will be readily seen that I have provided an exceedingly simple tie which is indestructible and may be produced at a cost which is low considered in the light of the durability of the tie. The caps may be easily and quickly slid into engagement with the rails so that the rails will be firmly held and spreading of the rails will be positively prevented. The hollow formation of the ties will permit anchoring means to be inserted into them if considered desirable or advantageous, and the caps will effectually cover the openings in the tie so that the entrance of any objects which might tend to dislodge the rails will be prevented.

Having thus described the invention, what is claimed as new is:

In a railroad track, the combination of

a tie provided in its upper portion with transverse slots and having longitudinally disposed notches in the its side walls, the open ends of the notches being located in the adjacent vertical end walls of the slots at the bases of the same, the opposite end walls of the slots inclining upwardly away from said vertical end walls, track rails seated in the lower ends of the said slots and having their base flanges at one side fitting snugly in said notches, the webs of the rails abutting the adjacent vertical end walls of the slots, caps slidably mounted upon the tie to extend over the slots and abut the webs of the track rails and provided in their side walls at the ends abutting the track rails with notches fitting snugly around one base flange of the track rail whereby the rails will be held by and in the notches of the caps and the tie, and fastening devices inserted through the side walls of the cap and the tie.

In testimony whereof I affix my signature.

CLARENCE E. TAYLOR. [L. S.]
